UNITED STATES PATENT OFFICE

160,499

TOY BOAT

Henry S. Hughes, Belmont, Calif.

Application December 8, 1948, Serial No. 150,035

Term of patent 7 years

(Cl. D34—15)

To all whom it may concern:

Be it known that I, Henry S. Hughes, a citizen of the United States and residing at Belmont, California, have invented a new, original, and ornamental Design for a Toy Boat, of which the following is a specification, reference being had to the accompanying drawing, forming part thereof.

Figure 1 is a side elevation of a toy boat showing my new design.

Figure 2 is a plan view of the toy boat illustrated in Figure 1.

Figure 3 is a front elevation of the toy boat illustrated in Figures 1 and 2.

Figure 4 is a rear elevation of the toy boat illustrated in Figures 1 to 3.

I claim:

The ornamental design for a toy boat, substantially as shown.

HENRY S. HUGHES.
